UNITED STATES PATENT OFFICE

105,678

DESIGN FOR A PIANO

William Zaiser, Rockville Centre, N. Y., assignor
to The Rudolph Wurlitzer Company, De Kalb, Ill., a corporation of Ohio

Application April 26, 1937, Serial No. 68,974

Term of patent 14 years

To all whom it may concern:

Be it known that I, William Zaiser, a citizen of the United States, residing in Rockville Centre, county of Nassau, and State of New York, have invented a new, original, and ornamental Design for a Piano, of which the following is a specification, reference being had to the accompanying drawing, forming a part thereof.

In the drawing:

Figure 1 is a three-quarter perspective view

showing the keyboard and one side of the piano embodying my new design.

end of the piano on a reduced scale.

I claim:

The ornamental design for a piano substantially as shown.

WILLIAM ZAISER.
